SAW SETTING MACHINE

Francis Louis Zingheim, San Jose, Calif.

Application April 30, 1932. Serial No. 608,513

3 Claims. (Cl. 76—62)

This invention relates to improvements in setting the teeth of saws.

The principal object of this invention is to provide a saw set which can be adjusted to set the teeth of various types and sizes of saws.

Another important object of the invention is to provide a saw set which can be trip operated or direct manually operated.

Still another important object of the invention is to provide a saw set which can be adjusted to vary the tension of the hammer, thereby controlling the force thereof in operation.

Other important objects and advantages of the invention will become apparent to the reader of the following specification.

In the drawings:—

Figure 1 represents a side elevational view of the novel machine.

Fig. 2 represents a front fragmentary elevational view of the machine.

Fig. 3 represents a vertical sectional view through the machine.

Fig. 4 represents a horizontal sectional view taken substantially on line 4—4 of Fig. 3.

Fig. 5 represents a side elevational view of the novel machine showing the circular saw mount attached thereto.

Fig. 6 represents a sectional view taken substantially on line 6—6 of Fig. 5.

Fig. 7 represents a cross sectional view taken substantially on line 7—7 of Fig. 5.

Referring to the drawings wherein like numerals designate like parts, it can be seen that the machine comprises a pair of side walls 5—6 projecting outwardly from wall plates 7—8, the wall plate 7 having a key slot 9 therein for receiving a suitable stud of the headed type which of course acts as a hanger when securing elements are being disposed through or removed from the opening 10 which further secures the side walls 5—6 to a supporting structure.

A block 11 is secured between the walls 5—6 by a bolt 12 extending therethrough and through the said side walls 5 and 6, and this block 11 has an upstanding member 13 provided with outward projections 14 and 15 having registering openings thereof for receiving the plunger 16 which has a suitably formed lower end 17 complementary with the counter-sunk beveled plate or anvil 18, the latter being located on the block 11 and secured thereto by a screw 19.

The plunger 16 is equipped with a collar 20 and interposed between this collar 20 and the projection 14 is a coiled compressible spring 22.

(See Fig. 3.) This spring 22 normally maintains the plunger urged upwardly.

Numerals 23 represents an arcuate-shaped hammer head, on which extends the shank 24, the said shank being provided with a foot 25 through which the bolt 26 extends and upon which the shank 24 is swingable. This bolt 26 passes through the side walls 5—6 and is equipped with a wing nut 27 whereby the bolt can be prevented from becoming displaced from the walls.

A foot 25 is provided with a claw 28 which is engageable with the shoulder 29 on the trip bar 30, the latter being slidable in the guide 31 and normally maintained urged upwardly against the stop 32 by the spring 33 which has its lower end connected to the lug 34 while its upper end connects to the anchor member 35 on the upper plate 7.

On the bar 30 opposite the lug 34 is the apertured lug 36 from which depends the swingable hook 37. This hook 37 can be engaged with the eye 38 at the upper end of the connecting rod 39 from which extends the foot pedal arm 40, or the hook 37 can be disengaged, and the hook 41 engaged with the eye 38 of the connecting rod 39, whereby the hammer 33 can be operated directly by the foot pedal 40 without the assistance of the trip bar 30.

The hook 41 is connected loosely as at 42 to the shank 24 adjacent the head 23. An adjustable spring 43 is interposed between the hammer shank 24 and the anchoring means 44 for normally maintaining the hammer in the desired position by operation by the foot pedal 40. The hammer 23 is obviously disposed immediately over the plunger 16 so that when the hammer is pulled downwardly it will swing the plunger 16.

When the hook 41 is attached to the foot pedal 40, obviously the full force of the foot exertion will be imparted to the hammer 23. However, when the hook 37 is attached to the foot pedal 40, only the force of the set spring 43 will be exerted.

A pair of guide members 45—45 are provided, one on each plate 5—6, each of these guides 45 including a transversely extending block 46 for receiving a bolt 47 operating in a horizontal slot of each side wall 5—6, and furthermore provided with a longitudinally extending slot 48 through which the aforementioned bolt extends, the bolt being provided with a wing nut 49, whereby the guide members 45 can be firmly secured to the said side walls 5—6.

Each of these guides 45 is provided with a re-

duced extension 50, and an arcuate-shaped finger 51 which is sufficiently curved to avoid the teeth of the saw, while at the same time riding on the top surface of the saw inwardly of the 5 teeth as in the manner substantially shown in Fig. 1.

Fig. 5 shows a slight modification in the form 10 of an attachment for the setting machine whereby circular saws can be accommodated. In place of the guide 45—45, plates 52 are supported by the aforementioned bolts 12 and 27 and from each of these plates extends the leg 53 of a U-shaped frame generally referred to by numeral 54 in Fig. 6.

15 Numeral 55 represents a slidable block having a pair of transversely extending grooves 56—56 in the bottom side thereof for receiving the leg portions 53 of the frame 54. Numeral 57 represents a clamp plate having a pair of narrow 20 ribs 58—58 on the ends thereof for abutting engagement with the said leg portions 53.

25 A bolt 59 extends downwardly through the block 56 and through the plate 57 where it is equipped with a wing nut 60, thus permitting the block and clamp to be clamped against the leg portions 53 of the frame 54.

The block 55 is provided with a circular opening 30 therein for receiving the cup 60, which is conical at its lower portion as at 61. The apex bottom portion of the cup 60 has an opening therethrough, thru which the threaded shank 62 of the cone 63 extends. This cone 63 is inversely disposed downwardly through the central opening in the circular saw 64 so that the 35 shank 62 thereof will depend downwardly through the cup 60 and through the opening in the lower portion thereof, where the shank is equipped with a wing nut 65, which when threaded inwardly on the shank, wedges the 40 cone 63 against the door and prevents displace-

ment of the door from the block 55. Thus the saw is firmly supported in place with its teeth interposed between the aforementioned plunger 16 and the anvil plate 18 of the setting machine. (See Fig. 5.)

80 While the foregoing specification sets forth the invention in specific terms, it is to be understood that numerous changes in the shape, size and materials may be resorted to without departing from the spirit and scope of the invention as claimed hereinafter.

85 Having thus described my invention, what I claim as new is:—

1. In a saw setting machine, a hammer, manual operating means for the hammer, and interchangeable means between the operating means and the hammer whereby the hammer is operated directly against the work by force or released to strike against the work by gravity.

90 2. In a saw setting machine, a hammer, manual operating means for the hammer, and interchangeable means between the operating means and the hammer whereby the hammer is operated directly against the work by force or released to strike against the work by gravity, and a spring for normally urging the hammer 95 toward the work.

100 3. In a saw setting machine, a hammer, manual operating means for the hammer, and interchangeable means between the operating means and the hammer whereby the hammer is operated directly against the work by force or released to strike against the work by gravity, said hammer being swingably mounted, a foot 105 extension on the fulcrum end of the hammer, 110 said interchangeable means including a trip device engageable with the said foot and a detachable connection extending from the head end of the hammer.
